UNITED STATES PATENT OFFICE.

OSWALD S. PULLIAM, OF PITTSBURG, PENNSYLVANIA, ASSIGNOR TO PITTSBURGH EQUIPMENT COMPANY, OF PITTSBURG, PENNSYLVANIA, A CORPORATION OF PENNSYLVANIA.

CAR-BOLSTER.

No. 886,070.

Specification of Letters Patent. Patented April 28, 1908.

Application filed September 16, 1907. Serial No. 393,109.

To all whom it may concern:

Be it known that I, OSWALD S. PULLIAM, of Pittsburgh, in the county of Allegheny and State of Pennsylvania, have invented certain new and useful Improvements in Car-Bolsters, of which the following is a specification.

My invention relates to improvements in car-bolsters and to this end the present invention consists of a new and improved car-
10 bolster, in the novel features of construction, and in the combination of parts all as fully herein described and claimed.

In the accompanying drawing, which illustrates applications of my invention, Figure 1
15 is a side elevational view partly in section of a truck-bolster embodying my invention; Fig. 2 a part plan and a part sectional view, the section being taken on line 2—2 of Fig. 1; and Figs. 3, 4, and 5 detail sectional views
20 showing modified forms of my invention.

Referring to the drawing, 1 designates the top-member of a bolster. This top-member, as illustrated and as preferred, is made of channel form and is provided with a center-
25 bearing plate or member 2.

3 designates a bottom-member of the bolster; this member is joined at its center to the center of the top-member by a king-post 4. Member 3 at each of its ends is formed
30 with a bent end-portion 5. These end-portions 5 are formed by bending the respective ends of member 3 back upon said member. In practice the said ends are bent back over a
35 filler or piece 6 and when so bent inclose or overlap said filler as clearly shown by the drawings.

The respective ends of the top and bottom-members 1 and 2 meet in end-members 7. Said end-members 7 are each provided with a
40 groove or recess 8 adapted to receive the respective bent end-portions 5 of the bottom-member 3, together with each of the fillers 6.

In the form of Fig. 4, I have shown the filler or piece 6 formed integral with the end-
45 member 7, while in the other forms illus.

trated, the filler 6 is a separate piece which may be joined to the respective ends of the bottom-member 3, before said ends are bent over, by means of bolts or rivets 9, as shown by Fig. 3.

By providing the pieces or fillers 6 the ends of the bottom-member may be bent over said fillers without fear of straining or weakening said bent-over ends of the bottom-member. In this construction, the fillers receive the
50 tension strains thereby preventing the bent-over portions of the bottom-member from pulling open, as has heretofore been the case.

Clips or engaging-members 10 are provided for the purpose of securing the ends of the top-member to the end-members; these clips are secured to the end-members by means of
55 rivets 11.

What I claim is:

1. A bolster comprising a top-member, a
60 bottom-member having an end-portion bent upon itself, a filler located in the bent-portion, an end-member formed to receive the
65 end bent-portion, and a clip secured to the
70 end-member and engaging an end of the top-member.

2. A bolster comprising a top-member, a
75 bottom-member having an end-portion bent upon itself, a filler located in the bent-portion, and an end-member provided with a
70 groove adapted to receive the end bent-portion and filler.

3. A bolster comprising a top-member, a
80 bottom-member having an end-portion bent upon itself, a filler located in the bent-portion, an end-member provided with a groove
85 to receive the bent-portion and filler, and a clip secured to the end-member and engaging an end of the top-member.

In testimony whereof I affix my signature
85 in presence of two witnesses.

OSWALD S. PULLIAM.
